MECHANICAL GAS VALVE

Friedrich Trudwig, New York, N. Y.

Application January 14, 1932. Serial No. 586,546

1 Claim. (Cl. 158—117.1)

The main object of this invention is to provide a gas valve which is automatically closed when the flame of a gas burner, of which the valve forms a part, is extinguished.

5 Another object of the invention is to provide a gas valve which is mechanically closed as the flame is extinguished by a thermostat which is deflected by the flame emanating from a gas burner.

10 The above and other objects will become apparent in the description of the invention in which characters of reference refer to like-named parts in the drawing.

Referring briefly to the drawing, Figure 1 is a 15 longitudinal, sectional, elevational view through the gas burner, showing the piston in open position.

Figure 2 is a top-plan view of Figure 1.

Figure 3 is a front-elevational view of the gas 20 burner and thermostat, showing the former in closed condition.

Figure 4 is an end elevational view of Figure 3.

Referring in detail to the drawing, the number 25 10 indicates the bell at the outer end of a gas burner. Into the usual opening of the bell, the nipple 11 of the gas burner body 12 is inserted. This gas burner body has a nipple 11 and a second diametrically opposite nipple 13 integral therewith. These nipples 11 and 13 are provided with aligned channels 14 and 15 respectively. The body 12 is provided with a bore 16 which extends at right angles to the channels 14 and 15 and communicates therewith. This bore 16 slidably receives a piston 17 which is provided intermediate its length with an annular recess 18 so that when the recess is aligned with the channels 14 and 15, communication is had between these channels 30 around the recess of the piston 17. To normally retain the piston in closed position a shank 19 is formed on said piston and is surmounted by a head 20 which has a rim 21 extending from its lower face. Into the confines of this 35 rim one end of a coil spring 22 is inserted. This coil spring is wound about the shank 19, and its opposite end rests upon the end of the valve body 12.

The lower end of the piston 17 is provided with 40 a flange 23 from which depends a T arm 24. This T arm is engaged by the bifurcated end 25 of a bell crank 26. The intersection of the arm of the bell crank is pivoted upon the extremity of a bracket 27. The opposite arm of 45 the bell crank 26 is hingedly connected to a

mover rod 28 which is joined to an ear 29 in a pivoted manner. The ear 29 forms part of the thermostatic blades 30. These blades are secured at their upper ends to a bracket 31 which is secured to the gas burner in close proximity 50 to a flame where the latter will effect the blades and deflect the same.

The piston 17 is preferably circular in cross-section, and when so constructed is provided with a runway 32. This runway 32 receives the 55 projecting end of a pin 33 which is embedded in the body 12 at its lower end and projects into the bore 16 of said body.

The device is adapted to automatically close when the flame is extinguished. The gas burner not shown has a bracket 31 mounted thereon in a position where the blades 30 of the thermostat member will be influenced by the flame. Normally the thermostatic blades are slightly curved as shown in Figure 3. To open the 70 valve a push button 20 is depressed until the upper limits of the runway 32 receives the pin 33. The position of the piston 17 after being depressed has its annular recess 18 aligned with the channels 14 and 15 of the nipples 11 and 80 13 respectively. In this position with the finger upon the push button 20, the gas will flow from the source of supply, into which the nipple 13 is tapped, directly to the burner through the bell 10. Igniting the gas will cause the burner 85 to flame and since this burner is placed in close proximity to the thermostatic blades 30 the latter will be deflected and will straighten to the position shown in Figure 4. This movement of the thermostatic blades will exert a 90 pull upon the rod 28 thereby rotating the bell crank 26 whose bifurcated end 25 engaging the T arm 24 will retain the piston 17 in lowered position thereby retaining the valve in open condition. 95

Should a gust of wind or liquid extinguish the flame the thermostat will immediately begin to deflect to its curved condition, and will thereby release the plunger 17, the spring 22 lifting said piston 17 to its raised position 100 where the flange 23 contacts with the lower end of the body 12, in which position the annular recess 18 assumes a position above the aligned channels 14 and 15 and closes the valve.

It is to be noted that certain changes in form 105 and construction may be made without departing from the spirit and scope of the invention.

I claim:

In a device of the class described, a valve body, a piston slidably therein having an annu- 110

lar recess, aligned opposing channels in said valve body, a shank on said piston, a button surmounting said shank, a coil spring wound about said shank seated on said valve body and 5 supporting said push button, said spring being adapted to lift said piston to a position where said recess disaligns with said channels to close said valve, a thermostat located remote from said valve in close proximity to a flame, a bell 10 crank pivoted on said valve body, a rod secured to said bell crank and thermostat for actuating said bell crank, said bell crank having a bifurcated end, an arm depending from said piston.

having right angled extensions supporting the bifurcated end of said bell crank, said bifurcated end rolling on said extensions when said bell crank is rotated, said arm engaging the bifurcated end of said bell crank and said bell crank 80 being adapted to lower said piston when said thermostat is deflected, a pin in said body, a runway in said piston, said pin projecting into said runway, said runway retaining said piston non-rotatable and limiting the movement of 85 said piston.

FRIEDRICH TRUDWIG.
